CLAIM

The ornamental design for a handle for golf pull-cart, as shown and described.

DESCRIPTION

FIG. 1 is a front, bottom, right isometric view of the handle for golf pull-cart showing our new design in the environment in which it is typically used.

FIG. 2 is a front, bottom, right, enlarged isometric view of the handle for golf pull-cart.

FIG. 3 is a front elevational view thereof; the rear elevational view is a mirror image thereof.

FIG. 4 is a right side elevational view thereof; the left side elevational view is a mirror image thereof.

FIG. 5 top plan view thereof; and,

FIG. 6 is a bottom plan view thereof.

The broken lines in the figures are for illustrative purposes only and form no part of the claimed design.
